UNITED STATES PATENT OFFICE.

HARRY H. LABADIE AND BURTON B. BEERS, OF CHICAGO, ILLINOIS; SAID BEERS
ASSIGNOR TO KNICKERBOCKER CASE COMPANY, OF CHICAGO, ILLINOIS, A CORPO-
RATION OF ILLINOIS.

SAMPLE CASE.

Application filed June 23, 1927. Serial No. 200,863.

This invention relates to sample cases, or similar display cases, and more particularly to a sample case of the type having a stack of trays nested therein which are extensible in 5 stair-like formation for displaying the contents of each tray and permitting access thereto.

One object of the invention is to provide a case of this type in which a plurality of 10 receptacles, comprising an upper tray, a lower drawer or tray, and a pocket on one hinged side of the case are all readily accessible without extending the stack of trays from the casing.

15 Another object is to so mount the stack of trays within the casing that the lowermost tray will be housed above the lower removable drawer when the trays are nested within the casing, but will move down to form 20 a supporting means for the lower end of the stack when the stacked trays are extended from the casing.

Other objects and advantages of this invention will be more apparent from the following 25 detailed description of one approved form of sample case built according to the principles of this invention.

In the accompanying drawings:

Fig. 1 is a perspective view of the sample 30 case when closed.

Fig. 2 is a perspective view of the case with the hinged top and side open.

Fig. 3 is a vertical central section through the lower portion of the case, when in the 35 position shown in Fig. 2.

Fig. 4 is a perspective view of the case with the stack of trays extended.

Fig. 5 is a detail view of one of the hinge 40 mountings for the upper end of the stack, this view being a section taken substantially on the line 5—5 of Fig. 4.

The outer casing 1 comprises a bottom 2, a vertical side 3 and ends 4 and 5, all of which parts are rigidly united in a usual manner. 45 The other side wall 6 is hinged to the bottom 2 at 7 so that it may be swung down into substantially the same horizontal plane as the base or bottom 2 of the casing. When in closed or vertical position it is parallel with 50 the fixed vertical wall 3 of the casing. The top or cover 8 is hinged to the upper edge of the side wall 3, and when opened is swung back to the position indicated in Figs. 2 and 4. The hinged side 6 is provided with edge 55 flanges 9 adapted to overlap the adjacent

edges of the end walls 4 and 5, and the top or cover 8 has a side flange 10 and end flanges 11 adapted to overlap the upper edges of the side wall 6 and end walls 4 and 5 respectively when the casing is closed as shown in Fig. 1. Suitable locks or clasps 12, the parts of which are secured to the adjacent edges of the top 8 and side wall 6 serve to secure the members of the casing together in this closed position, all as illustrated in Fig. 1. A suitable handle 13 60 may be mounted on the cover 8 for transporting the sample case from place to place.

A horizontal partition 14 is secured to the end walls 4 and 5 and the rear wall 3, in spaced relation to the bottom 2 of the casing. A removable drawer or tray 15, closed at the sides and bottom but open at the top, is removably housed in the space beneath the partition 14. A tab 16 permits this drawer 15 to be easily 65 pulled out so that its contents are visible and accessible. A flexible pocket 17 provided with a snap closure 18 is mounted on the inner face of the hinged side member 6, and may conveniently be used for carrying books, pamphlets, or papers of any sort.

80 A stack of trays, preferably comprising a relatively deep upper tray 19 and a series of similar shallower trays 20 to 25 inclusive, are normally housed when in nested position in the space within the casing above partition 14. The number and depth of the respective trays is a matter of choice and need not be as herein described and shown. Each tray is preferably closed at its bottom and sides, but open at the top, as illustrated in 85 the drawings. Reinforcing strips 26 are riveted or otherwise secured adjacent the upper edges of the ends of the upper tray 19, and the rear ends of these strips are hinged at 27 to the upper ends of brackets 28 secured 90 at 29 within the upper ends of the end walls 4 and 5 of the casing. Reinforcing strips 30 are secured near the lower edges of the end walls of tray 19, and similar strips 31 are secured at suitable locations (as herein- 95 after described) to the respective end walls of the trays 20 to 25 inclusive. These reinforcing strips 30 and 31 are pivotally connected by a plurality of links in a lazy-tongs formation, as clearly shown in Fig. 4. It 100 will be noted that a short link 32 is pivoted at the center of the reinforcing strip 31 of the bottom tray 25, and is pivoted at its upper end to the forward end of reinforcing strip 31 on the next higher tray 24. A longer 105

link 33 is intermediately pivoted to the center of strip 31 on tray 24, and is pivoted at its upper and lower ends respectively to the front and rear ends respectively of the strips 31 on trays 23 and 25. All of the other trays 5 are connected in a similar manner. The lengths of the links 32 and 33, and the positioning of the strips 31 on the ends of the respective trays is such that when the trays 10 are moved to nested or stacked position, as shown in Fig. 2, each tray will rest directly upon the upper surface of the tray therebelow. However, when the trays are extended in stair-like formation, as shown in Fig. 15 4, the respective trays will be spaced vertically from one another so that the lower tray 25 will move down to substantially the horizontal plane of the base 2 of the casing. In this manner, the lower end of the stack, when 20 extended, is supported upon either the lowered side wall 6 or the horizontal supporting surface upon which the sample case rests. On the other hand, when the trays are moved into stacked or nested position within the casing, the lower tray 25 will fit snugly above 25 the partition 14 so that the lower drawer 15 is freely accessible. A tab 34 may be secured to the lower front edge of the bottom tray 25 to facilitate pulling the stack out to 30 extended position. In this opening movement the lower edge of the nested stacks is first swung out about the pivot 27, since this pivotal axis is located above the rear edge of the stack of trays, it will be apparent that 35 the trays can swing upwardly and outwardly so as to clear the partition 14 before they are extended. This construction permits the nested or stacked trays to fit snugly above the partition 14 when in closed position.

40 It will be apparent that by simply unfastening the clasps 12 the cover 8 may be lifted and the side wall 6 will drop to open position. The large upper tray 19 and the pocket 17 on the inner side of side wall 6 are now 45 readily accessible, and the large bottom drawer 15 may be pulled out without disturbing the stacked trays. All of the articles ordinarily needed may be carried in these three readily accessible receptacles so that it may 50 not be necessary to extend the stacked trays 19 to 25 inclusive. If it is desirable to expose the articles or samples carried in the several trays of the stack, it is only necessary to pull out on the tab 34 and extend the trays 55 to the position shown in Fig. 4. The case may be reassembled by simply reversing the operations just described.

We claim:

1. A sample case comprising a casing having an open side and a horizontal partition spaced from the bottom of the casing, a removable drawer housed in the space beneath the partition, a stack of trays housed in the space above the partition with the uppermost drawer hinged within the casing, and a plu-

rality of links connecting the trays in lazy-tongs formation so that the trays may be extended from the casing in stair-like manner with the lower tray in position to be supported substantially in the plane of the bottom of the casing. 70

2. A sample case comprising a casing having an open side, a removable drawer housed in the lower portion of the casing, a stack of trays housed in the space above the drawer with the uppermost tray hinged within the casing, and a plurality of links connecting the trays in lazy-tongs formation so that the trays may be extended from the casing in stair-like manner with the lower tray in position to be supported substantially in the plane of the bottom of the casing. 75

3. A sample case comprising a casing having an open top and side each provided with hinged closures and a horizontal partition spaced from the bottom of the casing, a stack of trays housed in the space above the partition with the uppermost tray hinged within the casing, and a plurality of links connecting the trays in lazy-tongs formation so that the trays may be extended from the casing in stair-like manner with the lower tray in position to be supported substantially in the plane of the bottom of the casing. 80

4. A sample case comprising a casing having a hinged top and a hinged side adapted to swing down into the plane of the bottom of the casing so that one side of the casing will be open, a drawer housed within the lower portion of the casing and removable through the open side, a stack of trays housed in the space above the drawer with the uppermost tray hinged within the casing, and a plurality of links connecting the trays in lazy-tongs formation so that the trays may be extended from the casing in stair-like manner with the lower tray in position to be supported in the plane of the bottom of the casing. 95

5. A sample case comprising a casing having an open top and one open side, a side member hinged to the bottom of the casing and adapted to close the open side or swing down into substantially the plane of the bottom of the casing, a top member hinged to the upper edge of the casing and provided with downwardly extending flanges adapted to enclose the upper edges of the sides and ends and hold the hinged side in closed position, clasps on the hinged top and side for securing these members in closed position, a horizontal partition within the casing and spaced from the bottom thereof, a drawer housed in the space beneath the partition and removable through the open side of the casing, a stack of trays housed in the space above the partition with the uppermost tray hinged within the casing, and a plurality of links connecting the trays in lazy-tongs formation so that the trays may be extended from the casing in stair-like manner with the 100

110

115

lower tray in position to be supported substantially in the plane of the bottom of the casing.

6. A sample case comprising a casing having an open top and one open side, a side member hinged to the bottom of the casing and adapted to close the open side or swing down into substantially the plane of the bottom of the casing, a pocket mounted on the 10 inner face of the hinged side, a top member hinged to the upper edge of the casing and provided with downwardly extending flanges adapted to enclose the upper edges of the sides and ends and hold the hinged side in closed 15 position, clasps on the hinged top and side for
- securing these members in closed position, a horizontal partition within the casing and spaced from the bottom thereof, a drawer housed in the space beneath the partition and removable through the open side of the cas- 20 ing, a stack of trays housed in the space above the partition with the uppermost tray hinged within the casing, and a plurality of links connecting the trays in lazy-tongs formation so that the trays may be extended from the 25 casing in stair-like manner with the lower tray in position to be supported substantially in the plane of the bottom of the casing.
